DROP COIN TIMING DEVICE
Louis Eickhoff, % Robco Corp., 235 Main St.,
Patchogue, N.Y.
Filed June 20, 1961, Ser. No. 118,354
2 Claims. (Cl. 194—1)

This invention relates to coin operated timing devices and particularly to a novel simplified device which utilizes dropped coins to actuate a timing motor and permits an accumulation of coins to establish selected timing intervals.

Dropped coins have been utilized in the past to strike the arm of an electric switch and actuate a timing motor for a fixed period. It was difficult, however, to accumulate these coins to provide multiple units of time or permit selection of different intervals. Other devices have utilized coin slides and rotary stepped gear or ratchet arrangements to adjustably advance a shaft in accordance with the number of coins inserted. A timing motor then returns the shaft to the starting position within the selected interval. These devices, while providing time variations, are relatively complex and costly.

It is, therefore, the object of the present invention to provide a simple device permitting an accumulation of dropped coins to establish corresponding selective intervals of time.

The instant device utilizes a novel horizontal gear and lower plate arranged in layers and having slots there-through to receive the coins. A tube accumulates the dropped coins above the gear and plate. The coins are directed by the tube to rest upon a button or rod which is connected through the slot in the gear and plate to a lever positioned above the arm of an electric switch. Each coin depresses the button to actuate the switch and motor and falls into a round slot in the gear. The lower slot in the plate accommodates only the shape of the button so that the coin holds the button down and is carried by the gear. The motor then drives the gear which prevents the button from re-entering the tube until another slot or the same one rotates into the original position to accept a second coin. During this time, the first coin drops out through a second round slot in the plate. Thereafter, the second coin starts an additional timing cycle.

The detailed description and accompanying drawings which follow consider the invention in a particular configuration. It is to be understood that this represents but one embodiment chosen for the purpose of explanation and illustration and is not to be construed as defining the limits of the instant invention.

FIG. 1 is a front view and vertical section of the novel timing device showing an accumulation of coins.

FIG. 2 is a vertical section on the line 2—2 of FIG. 1, showing the device without coins.

FIG. 3 is a side view of said device.

FIG. 4 is a horizontal section showing the elements of the instant device.

FIG. 5 is a vertical section on the line 5—5 of FIG. 3.

As shown in FIG. 1, coins 10 are inserted into a front panel slot (not shown) and fall into a chute 12 which guides the coin into a tube 14 where they are accumulated in a vertical stack. The tube is mounted above a rotatable gear 16 which has a round slot 18 to accommodate the coin. The first, or lowest, coin rests in the slot below the tube upon a button or rod 20 at one end of lever 22 which is pivotally secured below the gear at point 24 to support structure 26, as shown more clearly in FIGS. 2 and 3. The button moves lever 22 down to depress arm 28 of electric switch 30 and actuates timing motor 32.

When there are no coins in the tube, as shown in FIGS. 2 and 4, the spring action of arm 28 and a weight 34, acting about point 24, tend to normally urge the button up into the tube. The weight of the coin then forces the

2

button down and the coin falls into slot 18 in gear 16. The button in turn fits into a smaller slot 36 in a stationary plate 38 immediately below the gear. Slot 36 is of a shape corresponding only to the button, so that coin is maintained within slot 18 of the gear.

When the motor is actuated by arm 28 a driving or pinion gear 40 secured to the motor shaft 42 causes gear 16 to rotate and carry the coin. Button 20 is then held in slot 36 below the moving gear. The coin thereafter passes over a second round slot 44 in the plate and falls into a collection box 46. If there are no further coins remaining in the tube, when the original coin slot 18 again reaches the starting point, the button is permitted to rise back into the tube. The switch arm and lever then rise and shut off the motor to complete one timing cycle. The gear and slot are then in position to receive the next coin. Additional coins, however, will cause the device to continue operation and to accumulate time until all the coins have been collected. Added coin slots may be provided through gear 16 at selected positions to make available shorter intervals of time. Further variations may be obtained by changing the driving or driven gear, or motor, to permit the use of other gear and speed ratios. In addition, an almost unlimited number of coins may be stacked in the tube, depending upon its height, to permit the accumulation of any desired period of time.

It may thus be seen that the present invention is a novel simplified dropped coin operated device which permits selection and accumulation of a wide range of timing intervals. While a particular embodiment of the invention has been illustrated, it is apparent that the device is not limited to the exact form or use indicated and that many variations may be made in the instant design and configuration without departing from the scope of the invention as set forth in the appended claims.

I claim:

1. A drop coin operated timing device comprising tubular means for accumulating a plurality of dropped coins in a vertically stacked position, rotatable means horizontally positioned below said tubular means and having a first slot adapted to receive and carry a coin from said tube, said slot being in alignment with said tube at a starting position, a stationary horizontal plate positioned below said rotatable means and having a second slot in vertical alignment with said tube, said second slot having a smaller dimension than said first slot to permit said plate to support said coin, electric switch means positioned below said plate, a timing motor adapted to be actuated by said switch to drive said rotatable means, coins operated lever means pivotally mounted to actuate said switch, said lever means having a vertical rod at one end adapted to fit through said first and second slots into said tube, said rod being normally urged upwardly in the absence of a coin and being adapted to be moved downwardly below said rotatable means by a coin falling thereon to actuate said switch and motor, said rotatable means preventing said rod from returning into said tube until the completion of a first timing interval and a realignment of slots, means for collecting said coins including a third slot in said plate adapted to receive said coin from said rotatable means and permit said coin to fall through, and a container for holding said coin after falling through said plate, said motor driving said rotatable means into position to permit said rod to move upwardly through said second slot to stop said motor and complete said first timing interval and to accept a second coin to start a second timing interval, said rotatable means comprising a first gear and said timing motor including a second gear adapted to drive said first gear, and said first gear having a plurality of selectively spaced slots to receive coins to provide shorter timing intervals.

2. A drop coin operated timing device comprising tubular means for accumulating a plurality of dropped coins in a vertically stacked position, rotatable means horizontally positioned below said tubular means and having a first slot adapted to receive and carry a coin from said tube, said slot being in alignment with said tube at a starting position, a stationary horizontal plate positioned below said rotatable means and having a second slot in vertical alignment with said tube, said second slot having a smaller dimension than said first slot to permit said plate to support said coin, electric switch means positioned below said plate, a timing motor adapted to be actuated by said switch to drive said rotatable means, coin operated lever means pivotally mounted to actuate said switch, said lever means having a vertical rod at one end adapted to fit through said first and second slots into said tube, said rod being normally urged upwardly in the absence of a coin and being adapted to be moved downwardly below said rotatable means by a coin falling thereon to actuate said switch and motor, said rotatable means preventing said rod from returning into said tube until the comple-

tion of a first timing interval and a realignment of slots, means for collecting said coins including a third slot in said plate adapted to receive said coin from said rotatable means and permit said coin to fall through, and a container 5 for holding said coin after falling through said plate, said motor driving said rotatable means into position to permit said rod to move upwardly through said second slot to stop said motor and complete said first timing interval and to accept a second coin to start a second timing interval, said rotatable means comprising a first gear and said timing motor including a second gear adapted to drive said first gear, and means urging said rod in an upward position including a weight mounted at the other end of said pivotal lever and a resilient actuating arm engaging said lever and switch.
